KNITTING MACHINE

Herman E. Crawford, Kernersville, and Cecil Crawford, Durham, N. C.

Application July 16, 1946, Serial No. 683,846

4 Claims. (Cl. 66—9)

1

This invention relates to a knitting machine having means for knitting a very loose stitch fabric and laying into the fabric an elastic strand by placing the strand in front of some needles and behind other needles and advancing the sinkers at the knitting point, so that the one or more top yarns which are placed into the knitting machine will be knitted while on top of the advanced sinkers, thus providing very elongated loops, while the elastic yarn is incorporated into the fabric. This gives a very much greater stretchability to the fabric and permits it to be stretched to a much greater extent, causing it to fit the leg of the wearer without undue pressure on the leg.

The machine also embodies pattern control means for selecting the needles which will take the elastic yarn, that is, the needles which will rise in front of the elastic yarn and those which will rise behind the elastic yarn, so that a design can be formed on the fabric merely by the manner in which the elastic yarn is incorporated into the fabric. For example, if the elastic yarn is laid on the inside of the fabric behind three wales, for example, and then laid in front of one needle and behind another needle for a plurality of wales, it is evident that the tension of the elastic yarn will cause the three wales behind which the elastic yarn is disposed to protrude on the inside of the fabric and causing that portion of the fabric to be raised or outwardly projected to produce a ribbed effect, thus forming a design on the exterior of the stocking, of the same color, of course, as the remainder of the stocking on account of the selection of needles. Means are also provided whereby different needles can be selected upon successive courses so as to form any desired pattern.

Also means are provided for engaging the fabric and pressing it downwardly on the sinkers so as to cause a proper shedding of the loops, when the needles are lowered in a knitting operation, and this is a desirable feature, since there is no body yarn disposed below the nibs of the sinkers to hold the fabric down, and thus insure shedding of the fabric from the needles. By providing a corrugated roller set at an angle and pressing the fabric downwardly off the ends of the sinkers, the fabric is thus insured in its shedding off the needles during a knitting operation.

Some of the main features of the invention having been set forth, the various mechanisms in the machine and the advantages thereof will

2

appear more fully in a detailed description which hereinafter follows.

This invention also relates to an improved method and means of making seamless knit elastic hosiery. It is well known throughout the trade that all known methods such as laying-in elastic yarn and knitting-in elastic yarn does not produce a desirable fabric for elastic top stockings or stockings made with the elastic yarn incorporated throughout the stockings because the fabric, in which the elastic yarn is incorporated is knit with regular size loops or stitches or with tuck stitches; it is also known that the regular size stitches hold the elastic yarn in such a manner that the elastic yarn cannot slip between the stitches thus causing the elastic yarn to break when the fabric is stretched. It is also well known that when tuck stitches are made in order to loosen the fabric, the desired result is not obtained because the tucked stitches cause the fabric to be wide and bulky so that the elastic yarn cannot draw the fabric—to make the top or stocking or elastic portion as narrow as it should be to properly fit the ankle. Another purpose of this invention is an improved elastic fabric whereby the simulated ribs or protruding portions of the fabric are much more noticeable and this is a much desired effect.

These improvements are accomplished by knitting all of the loops 30% to 100% longer than regular loops or stitches and by using 30% to 100% heavier yarn than would be possible to knit without our invention. By knitting the fabric loose or making the loops 30% to 100% longer, the elastic yarn or strand can be stretched to its fullest extent because all the loops are loose and do not bind the elastic strand at any point. By knitting the fabric with 30% to 100% heavier yarn than could otherwise be used (To explain: If two ends of #12 yarn is used for making the plain knit fabric of a stocking, 3 ends of #12 yarn would be used in making the top or elastic portion of the stocking; or if one end of #8 yarn is used in making the plain knit part of the stocking, two ends of #8 yarn could be used in making the elastic top or that portion of the stocking which may be made with elastic yarn) the ribbed or protruding portions of the fabric are much more noticeable and because the stitches are loose, the elastic yarn will draw the fabric to its proper width and this is a very desirable effect.

Referring broadly to the drawings,

Figure 1 is a front elevation of the top portion of a machine equipped with my apparatus;

Figure 1a is a front elevation of the lower portion of said machine;

Figure 2 is an elevation looking at the upper portion of the left hand side of the machine;

Figure 2a is an elevation looking at the lower left hand side of the machine;

Figure 3 is an elevation looking at the right hand side of the machine in Figures 1 and 1a, and omitting much of the top portion of the machine;

Figure 4 is a top plan view of the machine showing some of my apparatus in position thereon;

Figure 5 is a top plan view of the lower portion of Figure 4 and showing the same on a much larger scale and showing the latch guard ring removed;

Figure 6 is a vertical sectional view taken along the line 6—6 in Figure 4 with certain parts omitted and showing the shedding wheel in operative position;

Figure 7 is a view similar to Figure 6, but showing the shedding wheel in raised and inoperative position;

Figure 8 is a vertical sectional view through the pattern cylinder for controlling the selection of needles, which position the elastic yarn in the stocking;

Figure 9 is a horizontal sectional view looking downward and taken along the line 9—9 in Figure 8, and showing the ratchet wheel for advancing the needle selecting pattern cylinder;

Figure 10 is a schematic view showing needles and sinkers in one position;

Figure 11 is a view similar to Figure 10, but showing the parts in the different positions;

Figure 12 is a view similar to the preceding figure, but showing the parts in still another position;

Figure 13 is a view similar to the preceding figure, but showing the parts in still another position;

Figure 14 is an exploded view of a portion of the needle cylinder and the jack elevating cams;

Figure 15 is an elevation of a stocking made on this machine with the needle selecting cylinder cammed as shown in the drawings to make a given design;

Figure 16 is a schematic diagram of the fabric taken on enlarged scale and showing that portion of the stocking in Figure 15, which is enclosed within the dotted square;

Figure 17 is a vertical sectional view taken along the line 17—17 in Figure 2a;

Figure 18 is a vertical sectional view taken along the line 18—18 in Figure 4;

Figure 19 is an elevation of the lower right hand portion of the machine, and looking from substantially along the line 19—19 in Figure 3;

Figure 20 is a vertical sectional view through the elastic yarn feed and taken along the line 20—20 in Figure 4;

Figure 21 is a view partly in section and partly in elevation, and taken along the line 21—21 in Figure 3.

Figure 22 is an elevation looking from along the line 22—22 in Figure 3.

Referring more specifically to the drawings, the numeral 10 indicates the main body portion of the machine having a top plate 11, a needle cylinder 12, a sinker guide ring 13, a latch guide ring 14, and a pulley 15 for driving the machine. This pulley is the conventional split pulley type comprising loose and tight pulleys. The machine is also equipped with a main pattern shaft 16,

having a main pattern drum, not shown, and a pattern chain 19, having a left hand extension pattern drum 21 and a right hand extension pattern drum 22 mounted on said main pattern shaft. The machine also has several yarn feed fingers 17 for feeding one or more inelastic or top yarns 18 to the needles.

In making the stocking, a heavy yarn is used in connection with the elastic yarn. Usually 10 there is fed to the needles during the knitting with elastic yarn, one or more body yarns having a total denier of from 30 to 100 percent heavier than could be used in a machine of this type. A machine of this type could not use this heavy 15 yarn unless all of the sinkers were advanced at the knitting point to produce a very loose stitch.

The needle cylinder 12 has a plurality of conventional needles 24 of the latch type, the long butt needles being indicated by reference character 25 and the short butt needles being indicated by reference character 26. The cylinder is also equipped with long and short butt jacks, the long butt jacks being indicated at 27, and the short butt jacks at 28. The long and short butts 25 on the needles and jacks are also indicated by L and S respectively.

The knitting machine also has a plurality of sinkers 31, which are guided in their path in a conventional manner by the sinker guide cap 13.

30 The machine is also equipped with a suitable plate 33 disposed within the needle circle on which is disposed a conventional elastic strand clamp and cutter 35, having an upwardly projecting arm 36 to which a link 37 is connected and this link 37 has a collar 38 thereon (see Figures 1 and 7). A tension spring 41 normally holds the clamps cutter in closed position.

The link 37 slidably penetrates an arm 42 mounted on a pin 43 on the latch guide ring and 40 integral with the upwardly projecting arm 42 is another arm 44, which is adapted to rest against a collar 46 disposed on the upper end of a link 47, mounted for sliding movement in a bracket 48 secured on the framework of the machine.

45 Pivoted to the lower end of link 47 is a lever 51, which is pivoted as at 52, and the other end thereof has a conventional push rod connected thereto which extends down through the machine, and is connected to a suitable lever 53, pivoted on a bolt 49, which lever 53 has a link 54 secured thereto which projects to the right in Figure 19 and has an inwardly projecting portion adapted to follow the first row of cams 50 on the right hand extension drum 22. On the left 55 hand side of the machine are two studs 55 and 56, on which a plurality of levers are pivotally mounted for following the left hand extension pattern drum 21.

The top plate 11 of the machine has mounted 60 thereon a suitable plate 60, which has rising upwardly therefrom a pin or shaft 61, on which is mounted a plurality of jack raising levers 62, 63, 64, 65, 66, 67, 68, and 69. The right hand end of these levers 62 to 69 inclusive, shown in Figure 1, 65 are much thinner at their inner edge which engages the butts of the jacks, than at their outer edge. The other ends of these levers 62 to 69 each have a tension spring 71 connected thereto, whose other ends are connected to a 70 post 72 rising from the plate 60.

Rotatably mounted in plate 60 is an uprising shaft 73, whose upper end is rotatably supported by a bracket 74 extending from the framework of the machine. This uprising shaft 73 has a 75 vane 75 extending therefrom so that when this

vertical shaft 73 is oscillated, it will move the left hand end of the jack selecting levers 62 to 68 inclusive away from the observer in Figure 1 and will, therefore, withdraw the knife edged other ends of the butt engaging levers 62 to 68 from out of the path of the butts on the jacks in the needle cylinder.

Each of the jack selecting levers 62 to 69 inclusive has a projection 77 on its front side for engaging the cam members 106 on the jack selecting pattern drum to be presently described.

The lower end of shaft 73 has an arm 81 adjustably secured thereon (Figures 1 and 2), the free end of which is slidably penetrated by a link 82 having a collar 83 adjustably secured thereon, and the other end of the link 82 is pivotally secured, as at 84, to one end of a bell crank 85, pivoted as at 86, on a bracket 87 secured to the bed plate 11 of the machine.

The other end of this bell crank 85 has pivotally secured thereto, as at 88, a downwardly projecting link 89, having in its lower end a slot 91 penetrated by a screw 92 threadably secured in a crosspiece member 93 secured to the outer end of the left extension drum 21. This link 89 has a roller 94 thereon, which is adapted to ride onto low cam 95, while knitting from point B to point B' Figure 15 to take the pattern out of the back of the stocking by not raising the short butt jacks. The roller 94 then rides onto high cam 97 to remove the pattern entirely while knitting the heel. The roller 84 then falls onto low cam 98 which allows the jack selecting levers to make the pattern only in the top of the foot portion. The roller 84 then rides onto a high cam 96 of the left extension pattern drum 21 to remove all of the pattern from the toe portion. When the roller 94 is riding on the low cams 95 and 98, it will move the jack selecting levers to a midway point to where there cammed knife edged ends will engage the long butt jacks, but not the short butt jacks.

When the roller 94 is riding on the high cam 96, then the cammed ends of the butt engaging levers 62 to 68 inclusive will be moved to such a position that they will not engage the short butt or the long butt jacks for the needles.

Threadably mounted in the plate 60 (Figure 8) is the lower end of a stud bolt 100 and rotatably mounted around this stud bolt 100 and immediately above the top of plate 60 is a pair of oscillating levers 101 and 102. The levers 101 and 102 are oscillatably mounted around a downwardly extending portion 103 of a jack selecting pattern drum 104, which is rotatably mounted on the shaft 100.

The periphery of drum 104 has a plurality of threaded holes 105 therein, which are arranged in vertical and circumferential rows, and in these threaded holes screws 106 are adapted to be selectively placed for a particular pattern, said screws engaging the projections 77 on the levers 62 to 68 inclusive for effecting selection of needle selecting jacks.

Secured to the lower surface of pattern drum 104 is a ratchet wheel 107, having 26 teeth in its periphery, 25 of these teeth being full length teeth and one of the 26 designated as 108 being only half length for purposes to be presently described. This ratchet wheel is secured to the lower end of the pattern drum 104 by any suitable means, such as screws 111. More than the upper half of the pattern drum 104 is hollow, providing a cavity, in which a plate 112 is disposed and which plate is penetrated by a screw 113, which is

threadably embedded in the upper end of post 100 to secure the plate 112 to post 100.

Plate 112 has threadably secured therein three setscrews 114, which penetrate the plate 112, and each engage respectively compression springs 115, whose lower ends press against a plunger 116, only two of which are shown in Figure 8, which in turn press against the upper central portion of the lower portion 103 in the jack selecting pattern drum 104. This gives the proper amount of friction to prevent undue rotation of the pattern drum 104, except when moved, as desired.

Each of the compression springs 115 and the plungers 116 are mounted in suitable vertically disposed bores 118. The bores 118 are disposed in a suitable cylindrical member 119, which is integral with the plate 112.

The top lever 102 has pivotally secured thereon by means of a shoulder screw 122 a dog 121, having a point 123 adapted to engage the teeth in ratchet wheel 107. This dog is urged against the ratchet wheel by means of a tension spring 124 secured to its free end and secured to a spring perch 125 secured on the lever 102. The free end of dog 121 has a pin 126 projecting downwardly from the lower surface thereof adapted to be engaged by a cam on lever 101 to be presently described.

The lever 102 at its free end has pivoted thereto, as at 127, a link 128 normally urged to the right in Figure 5 by means of a tension spring 129. The upper end of this link 128 in Figure 4 is pivotally secured (see Figure 3) to a downwardly projecting arm 131 secured on a shaft 132 in bearings 133 secured to the top plate 11 of the machine.

The rear end of this oscillatable shaft 132 has secured thereto an arm 135 to the free end of which is pivotally secured a link 134 which projects downwardly and is pivotally secured, as at 136 (Figure 3), to a bell crank 138 which bell crank has a downwardly projecting portion 141 provided with a cammed surface 142, which is engaged by one or more cams 143 on the shaft of the 104 tooth gear of the machine. The bell crank 138 is pivotally secured as at 146.

Oscillation of this bell crank 138 by means of engaging the cam 143 on the shaft of the 104 tooth gear, oscillates the shaft 132 which will oscillate the arm 131, which will reciprocate the dog 121 to ratchet the pattern drum for selecting the needle selecting jacks. The bell crank 151 is normally urged in a clockwise direction in Figure 21 by a tension spring 150. If it is desired that the dog 121 do not reciprocate as the result of the bell crank 138 engaging the cam or cams 143 on the 104 tooth gear, there is provided another bell crank 151 (see Figure 21) pivoted, as at 152, to a bracket 153 on the framework of the machine, which has a shoulder 154 thereon which holds the bell crank 138 and locks it against oscillation, that is, it locks the downwardly projecting end, which has a cam surface 142 thereon, out of engagement with the cams on the shaft of the 104 tooth gear.

The lower portion of the bell crank 151 projects away from the machine and has pivotally secured thereto a link 156, which projects downwardly and slidably penetrates a pin 157 mounted on a lever 158, and the link 156 has a collar 161 thereon disposed below the pin 157. The lever 158 is pivoted, as at 163, and has its rear end normally urged downwardly by a tension spring 165.

The front end of lever 158 has a cam surface, which is adapted to engage a cam 159 on the right extension pattern drum 22, so that when the cam

end of lever is not disposed on a cam on the right extension pattern drum 22, it will allow the rear end of lever 158 to move downwardly, which will cause the shoulder 154 to move in a counter-clockwise direction in Figure 21, under the bell crank 138 and lock the bell crank in such position that its cam end 142 will not engage the cams on the 104 tooth gear hub and oscillate the dog 121. The lever 101, disposed below the jack selecting pattern drum 104, has mounted on its upper surface a cam member 170 (Figure 5), which, when the lever 101 is moved in a clockwise direction in Figure 5, will engage the pin 126 in dog 121 and move it out far enough so that during oscillation of dog 121 it will not engage the half-length tooth 108 of the ratchet wheel 107, but will engage the other teeth.

Lever 101 has pivotally secured thereto, as at 172, a link 173 normally urged to the right in Figure 5 or upwardly in Figure 4 by means of a tension spring 174 secured to a collar 175 on said link, and to a suitable spring perch 176 secured to plate 11 of the machine. This link 173 has a collar 177 on its end remote from lever 101, which fits against a downwardly projecting arm 180 secured on an oscillatable shaft 181 mounted in bearings 133 and immediately below shaft 132.

The rear end of shaft 181 has secured thereon an arm 182 to which is pivotally secured the upper end of link 183, which projects downwardly and slidably penetrates a pin similar to 157 secured in the rear end of a lever 187 pivotally mounted on stud 163. This is the middle lever on the right hand lower side of the machine, and it has on its front end a cammed surface adapted to engage a suitable cam 188 on the right extension pattern drum 22. When this lever 187 rides onto cam 188 on the right hand extension pattern drum 22, it causes the shaft 181 to oscillate to move the link 173 to the left in Figures 1 and 5 and causes the cam 170 to ride against the downwardly projecting pin 126 in dog 121 to move it outwardly against the tension of its spring 124 to where its pointed end 123 will not engage the short tooth 108 of the ratchet wheel 107 as previously described. Stud 163 has also pivotally mounted thereon a lever 190, the front end of which is adapted to contact cam 189 on right hand extension pattern drum 22, and to its rear end is pivotally connected to the lower end of an upwardly projecting link 192, having adjustably mounted thereon a collar 192a, which lever projects through the bed plate of the machine and is pivotally connected to the horizontal portion of a bell crank 194 pivoted, as at 195, and having pivoted at its upper end, as at 196, a link 197 which is pivoted, as at 198, to a bell crank 199, pivoted, as at 201, and having its free end adapted to engage a projection 202 on a link 203 pivoted, as at 204, and projecting over the needle circle and having a downwardly projecting shank 206 provided with a knurled roller 207, on its lower end, which is adapted to press the fabric 205 against the sinkers and to insure a shedding of the loops of the fabric from the needles in a lowering operation. The lever 203 is urged to the position shown in Figure 6 by a spring 200.

The lower butt selecting lever 69 is not moved to inoperative position by the vane 15 as it does not extend down far enough. This lower butt selecting lever 69 remains in operative position at all times unless it is moved to inoperative position by means of a link 210 pivoted to the end of the lever 69 nearest the observer in Figures 2 and 75

4, and having a tension spring 211 tending to move the non-cam end of lever 69 against the post 73.

The rear end of link 210 has a collar 213 thereon, to which the tension spring 211 is secured, 5 and the link 210 slidably penetrates a bell crank lever 214 pivoted as at 215 on a bracket 216 secured to the top plate of the machine. The rearwardly projecting horizontal portion of this bell crank 214 has pivotally secured thereto as at 217 a downwardly projecting link 218, whose lower end is pivoted, as at 219, to a lever 221 pivoted on the stud 56 (Figure 2a). The front end of this lever 221 is adapted to follow the second row 10 of cams 220 from the left in Figure 1a on left 15 extension pattern drum 21. If the cam end of this lever rides onto a cam on the extension pattern drum 21, it depresses the rear end of the lever 214, of course, and causes the cam end of lever 69 in Figure 2a to move away from the cylinder and from out of the path of butts of the jacks so that it will not engage the same while the needle cylinder is rotating. When it drops off of a cam, a spring 209 raises its rear end and this allows spring 211 to move the lowermost 20 25 selecting lever 69 to engage all the long butts of the set of the bottom butts at the lower portion of the cylinder. These long butts at the lower portion of the needle cylinder are present on every other jack, and the other jacks having 30 short butts.

The raising of the long butt jacks at the lower end of the jacks raises every other needle. All of the long and short butt jacks are first raised to where the jack selecting levers can engage 35 them by a conventional cam 208. With every other needle elevated by the lowermost selecting lever 69, they are in a position to be further elevated. This is accomplished by a lever 222 normally urged upwardly at its rear end by a tension spring 223. Lever 222 is pivoted on stud 55, which has a link 224 pivoted thereto, which extends upwardly and is connected to a bell crank 225, which is penetrated by a link 226, and 40 which link 226 is normally urged inward by a tension spring 227, the link 226 being connected to a cam lever 228 so that when the lever 222 rides onto a cam 222a on its associated pattern drum 21, it allows this spring 227 to pull the 45 elevating cam lever 228 inwardly to cause cam 228a (Figure 14), secured on lever 228 see (Figure 1) to engage the butts of the needles, which have been elevated by the previously described lowermost jack selecting lever 69. At the same time 50 a lever 231 pivoted on stud 55 is raised upwardly by a cam 231a and it has a link 232 pivotally connected thereto which extends upwardly and is pivotally connected to a bell crank 233, whose upper end is penetrated by a link 234 normally urged inwardly by a tension spring 236 so that when this last named lever rides onto a cam on the extension pattern drum 21, it raises the said link 234 and moves the upper end of its bell crank layer 233 inwardly, which allows the lowering 55 cam 237a (Figure 14) secured on lever 231 (Figure 1) to pivot inwardly to engage the butts of the same needles which have just been described as being elevated, and lower every other needle. This lowers these raised every other needles or any needles selected for the pattern down to a point to where they will enter the groove of the stitch cams and be guided into the regular stitch forming groove along with the other needles, which have not been raised heretofore, so as to place all of the needles in position to receive the 60 65 70 75

body yarn. The machine in this position is now ready to begin the make up course.

This time a lever 241 pivoted on stud 55 drops off its associated cam 241a on the extended pattern drum 21, which causes its rear end to rise, to which is slidably connected a link 242 having a collar 240 thereon. This allows link 242 to move upwardly under tension of a spring 243. Link 242 is pivotally connected at 246 to a lever 244 pivoted, as at 245. This allows the front end of the lever to be lowered and this front end of the lever has a laterally projecting portion 247, which is secured, as at 248, to lever 244 and on the inner surface thereof, there is a guard 251 and on the outer surface thereof a feeding portion 252 vertically adjustable by means of a slot 253 and having a horizontal portion 254 provided with a hole 255 and its lower end having a hole 256 through which the elastic strand 258 is fed to a point immediately outside of the needles, while the guard member 251 is disposed immediately on the inside of the needles in their travel around the needle circle. This operation places the elastic yarn feed into feeding position and the elastic yarn is caught on the raised needles, that is, the ones that have been raised by the selector cam 69 and the booster cam 228a, which booster cam is controlled by the lever 222 and which has already been described. The lever 244 has a stop member 249 secured thereon, which engages the top of the latch guard ring 14 and limits downward movement of the elastic yarn feed.

As the elastic yarn is introduced, it is knitted on the first three or four needles because when first introduced, it does not get below the latches of the raised needles. Thereafter it is deposited below the latches of the raised needles and, therefore, is laid in throughout the stocking. When the elastic yarn gets to the knitting point, then the body yarn is caught by the hooks of the needles and is knitted for one complete course without being placed on top of the sinkers. Before the sinkers are advanced at the knitting point to cause the body yarn to be laid on top of the advanced sinkers, and when one complete revolution has been made in the beginning of the stocking for the make up course, the sinkers at the knitting point are advanced slightly inwardly to cause the body yarn to be deposited on the tops of the nibs of the sinkers to knit the elongated loops.

The advancing of the sinkers at the knitting point is controlled by the fifth lever from the left in Figure 1a, this lever being designated by reference character 281 and is pivoted on lower stud 56. At its rear end it has pivotally connected thereto an uprising link 263 which is pivotally connected at its upper end to a horizontal portion of bell crank 264 whose vertical portion is adapted to move against a lever 265 pivoted to the cam plate of the machine as at 266 and having an outwardly projecting portion 266 to which a tension spring 262 is connected, which normally moves it in a clockwise direction looking down on top

Portion 266 has a set screw 267 secured thereto which presses against a cam member 268 pivoted as at 269 on the sinker guide ring 13 and tensioned by spring 270 to move out of sinker engaging position when not engaged by the set screw 267.

When the lever 281 is not on a cam 261a on the extended pattern drum 21, it allows tension spring 282 to move the sinker engaging cam into position where it will advance the sinkers at the knitting point and cause the body yarn to be laid on top

of the nibs of the sinkers. When it rides onto a cam 261a on the extended pattern drum 21, then the set screw is moved away from the sinker engaging cam 268, and its associated spring 270 moves it to non-engaging position with relation to the sinkers. After the make up course is completed, the sinkers are advanced at the knitting point and held in advanced position throughout the knitting of the entire stocking except during the knitting of the heel and toe.

The member 268 has adjustable eccentrics 271 and 272 which engage the sinker guide ring 13 and limit the swinging movement of member 268 in both directions.

15 A lever 275, which is the innermost lever mounted on stud 56, has connected thereto a link 276, which projects upwardly and is pivoted to a link 278, which is pivoted, as at 281, to the frame of the machine, which operates a suitable lever pivoted intermediate its ends in the machine 20 and which projects to the back of the machine and is connected to a suitable uprising link, not shown, which controls the take-up arms of the machine to take-up tension during heel and toe knitting.

25 In Figure 16, the wales are designated by reference characters 300 to 341 inclusive, and the courses are designated by reference characters 350 to 369 inclusive. In Figure 15, some of the 30 wales, but none of the courses, are designated by reference characters. By referring to Figure 15, attention is called to the fact that the vertical protuberances 1' and 11' are formed by the elastic strand being laid behind wales 335, 336, 35 and 337 throughout all of the courses, and vertical stripe 11' is formed in a like manner by laying an elastic strand behind wales 303, 304, and 305 throughout all the courses. Projecting portion 2' in Figure 15 is produced by laying the elastic 40 strand behind wales 327, 328 and 329, while knitting courses 351, 352, 353 and 354. Outwardly projecting portion or ridge 10' in Figure 15 is produced by laying the elastic strand behind wales 311, 312 and 313 in courses 351, 352, 353 45 and 354. Outwardly bulged portion 3' is produced by laying the elastic strand behind wales 325, 326 and 327 in courses 355, 356, 357 and 358. Outwardly bulged portion 9' in Figure 15 is produced by laying the elastic strand behind wales 50 313, 314, 315 in courses 355, 356, 357 and 358. Outwardly bulged portion 4' in Figure 15 is produced by laying the elastic strand behind the needles in wales 323, 324 and 325 in courses 359, 360, 361 55 and 362 and in these same courses the elastic strand is laid behind the needles in wales 315, 316 and 317 to produce outwardly bulged portion 8'. Outwardly bulged portion 5' in Figure 15 is produced by laying the elastic yarn behind the needles in wales 321, 322 and 323 in courses 363, 60 364, 365 and 366, and in these same courses, the elastic strand is laid behind wales 317, 318 and 319 to produce the outwardly bulged portion 7'. Outwardly bulged portion 6' appearing in Figure 16 where the elastic strand is laid behind the 65 needles in wales 319, 320 and 321 in courses 367, 368 and 369 and for a substantial distance further down the stocking than is shown in the schematic showing in Figure 16. When one-half of the diamond of protuberances has been formed 70 in the fabric, the jack selecting levers are moved in reverse order consecutively to form projection portions 12' and 13' which corresponds to protruding portions 1' and 5' and projecting portions 14' and 15' are formed in the same manner 75 as projecting portions 8' and 4' and projections

16' and 17' are formed in the same manner as projections 9' and 3'.

Method of operation

After the first make-up course is finished and the sinkers are moved inwardly, so as to knit the body yarn or yarn on top of the sinkers the stocking is then knitted as follows:

The roller 207 is lowered to aid shedding of the stitches. A number of courses of fabric is knitted with the elastic yarn in front of every other needle and in back of every other needle to make the top portion without the pattern or what is known as 1 x 1 rubber top fabric or 1 x 1 rib knitting. This is effected by the jack selecting levers 62 to 68 inclusive being held in inoperative position by vane 75 controlled by link 89 and roller 94 (Figure 2a).

This top portion of the stocking is made as described so as to set it off from the patterned or leg portion but it is not necessary to knit this portion of the stocking without the pattern if it is desired to make the pattern in this portion of the stocking. When a suitable portion of knitted fabric has been made for the top, which can be two courses or any number of courses desired, the patterning mechanism is then put into operation as follows:

The main pattern drum is caused to advance so that the roller 94 on link 89 drops off of cam 96 on left hand extension pattern drum 21. This will cause shaft 73 to move in a clockwise direction causing vane 75 to release selecting levers 62 and 68 inclusive allowing the projection 77 to engage the cam members 106 on the jack selecting pattern drum.

Where there are no cam members 106 on the jack selecting pattern drum, the jack selecting levers—cammed knife edge ends—will engage pattern jacks 1a to 11a as shown in Figure 14.

These pattern jacks 1a to 11a inclusive are arranged to make the pattern as shown in Figure 15. The cam surface on the lever 158 is engaged by a cam 159 on the right extension pattern drum 22 causing the shoulder 154 to move in a clockwise direction in Figure 21 and release bell crank 138 causing its cammed end 141 to engage the cam 143 on the 104 tooth gear hub causing the jack selecting pattern drum 104 to be ratcheted in a clockwise direction in Figure 5 each time cam 143 engages the cam surface 142 or bell crank 138.

The selection blocked off in dotted lines in Figure 15 shows a section of the pattern and having numbers from 1' to 11' inclusive so as to correspond with the pattern selecting jacks 1a to 11a in Figure 14.

This is explained as follows:

Pattern selecting jack 1a had 5 short butts, and pattern selecting jack 11a has 5 long butts at the proper level to be raised by levers 63 to 67 inclusive; the five pattern selecting levers 63 to 67 inclusive are used for making the pattern as shown in Figure 15. Levers 62 and 68 are not used in making this particular pattern.

While making the top portion of the pattern, or that part of the pattern above the heel, roller 94 is not on any cam but is resting on the left hand extension pattern drum 21 so that the vane 75 on uprising shaft 73 does not engage any of the pattern selecting levers 62 to 68 inclusive. When vane 75 is in this position the right hand end of the pattern selecting levers will engage both long and short butt pattern selecting jacks.

The screws 106 are so arranged in the pattern

selecting drum 104 that one of the five pattern selecting levers 63 to 67 inclusive is in position to engage the pattern selecting jack butts at all times during making of this pattern. The pattern selecting jacks 1a and 11a will be elevated every revolution of the needle cylinder and as pattern selecting lever 69 is raised every other jack, when jacks 1a and 11a are elevated, the needles will be placed in position so that the elastic thread will be placed under the latches of these three needles causing this portion of the fabric to be raised or outwardly protruded at positions 1' and 11' (Figure 15). The portions 2' and 10' of the pattern, Figure 15, is made when

jack selecting lever 67 is in position to elevate jacks 2a and 10a causing that portion of the pattern designated by 2' and 10' to be raised or outwardly projected. That portion of the pattern designated by 3' and 9' is made when jack selecting lever 66 is in position to elevate jacks 3a and 9a. That portion of the pattern designated by 4' and 8' is made when jack selecting lever 65 is in position to elevate jacks 4a and 8a. That portion of the pattern designated by 7' and 5' is made when jack selecting lever 64 is in position to elevate jacks 5a and 7a, and that portion of the pattern 6' is made when jack selecting lever 63 is in position to elevate pattern selecting jack 6a.

The stocking is completed and the pattern continued by jack selecting levers 63 to 67 inclusive continuing to be operated in the same manner as above described—that is—jack selecting levers 67 to 63 are caused to be in operating position 30 in consecutive order and then the number of the jack selecting levers is reversed and caused to be in operative positions 63 to 67 inclusive in consecutive order. When the stocking is knitted to point B, Figure 15, the main pattern drum is advanced forward so that roller 94 is riding on the low cam 95, causing vane 75 to be in a position to hold the jack selecting levers 62 to 67 inclusive so that they will only engage the long butt jacks 6a to 11a inclusive and all the pattern mechanisms continue to work as before but the pattern will only show in the front portion of the stocking where the pattern selecting jacks have long butts.

When the heel portion of the stocking is begun in the usual manner on seamless type knitting machines, roller 207 is raised out of operating position and lever 244 is raised so that the elastic yarn feeding finger is taken out of operative position to cause the elastic strand 258 to enter the elastic strand clamp and cutter 35 in Figure 7. This elastic strand clamp and cutter 35 holds the loose end of the elastic strand while the machine is knitting the heel portion of the stocking. The roller 94 is caused to rest on cam 97 on the left hand extension pattern drum 21, causing vane 75 to hold the pattern selecting levers 62 to 68 inclusive out of operating position.

Jack selecting lever 69 is caused to be moved out of operative position by the front end of lever 221 being held in an elevated position by cam 220 (Figure 14) on the left hand extension pattern drum 21 causing the rear end of lever 221 to be in a lowered position, causing the upper end of bell crank 214 (Figure 2), to be moved in an anti-clockwise direction causing link 210 to move the left end of pattern selecting lever 69 to the left in Figure 2. The front end of lever 158 drops off of cam 159 on the right hand extension pattern drum 22 causing the rear end of lever 158 to be moved downwardly by tension spring 165, causing

13

notch 154 on bell crank 151 to be positioned under bell crank 138 so that bell crank 138 will be in inoperative position so that the pattern selecting drum 104 will remain in a stationary position during the knitting of the heel portion of the stocking.

The front end of lever 261 is caused to rest on cam 261a on the left hand extension pattern drum 21, causing the rear end of lever 261 to be in a lower position, thus causing the lower portion of bell crank 264 to be moved downwardly, causing the upper end of bell crank 264 to be moved in a clockwise direction and this upper end of bell crank 264 engages lever 265 moving it in an anti-clockwise direction, causing set screw 267 to be moved away from cam 268 which is then caused to be in inoperative position by tension spring 270 so that cam 268 does not press the sinkers in under the yarn in the knitting of the heel portion of the stocking.

Lever 222 drops off of cam 222a on the left extension pattern drum 21 and needle raising cam 228a is moved away from needle cylinder 12 by uprising link 224 which is connected to lever 222.

Lever 231 drops off of cam 231a on left extension pattern drum 21 causing cam 237a to be moved away from cylinder 12 by uprising link 232 which is connected to lever 231. These two cams, 237a and 228a, are moved away from the cylinder so that the needles can be operated in their normal position for making the heel portion of the stocking.

After the heel portion of the stocking is completed, the operations just described are reversed and the machine continues to knit the pattern on the long butt jacks only until the ring-toe, or to the point marked C, Figure 15, is reached. When the stocking is completed down to the ring-toe, the main pattern drum is advanced forwardly and all the pattern mechanisms are taken out of operation as described above, when the machine begins the heel portion of the stocking.

In the drawings and specification, there has been set forth a preferred embodiment of the invention, and although specific terms are employed, they are used in a generic and descriptive sense only and not for purposes of limitation, the scope of the invention being defined in the claims.

We claim:

1. In a circular knitting machine having needles and sinkers and means for feeding body yarn to the needles and means for feeding an elastic strand to the needles, pattern controlled means for selectively raising some of the needles so as to cause the elastic strand to be disposed in front of some needles and behind other needles in selected order, the elastic strand being laid behind several needles and in front of a lesser number of needles to produce outwardly bulged portions in the fabric to thereby form a pattern, means for advancing the sinkers at the knitting point so as to knit all wales of the body yarn on top of the nibs of the sinkers to thus produce a very loose stitch so that the contraction of the fabric by the elastic yarn will cause the plurality of wales having the body yarn laid behind the same to bulge outwardly to produce a pattern effect, a member pivoted adjacent the needle circle and projecting over the needle circle and then projecting downwardly inside of the needle circle, a knurled roller rotatably mounted on the lower end of said member and disposed at an angle to the line of travel of the needles for resting on the fabric and holding it against the inner ends of the

14

sinkers to cause the fabric to shed from the needles upon lowering of the needles, and pattern controlled means for raising and lowering said roller to move it to operative or inoperative position, as desired.

2. In a circular knitting machine having needles and sinkers and means for feeding body yarn to the needles and means for feeding an elastic strand to the needles, pattern controlled means for selectively raising some of the needles so as to cause the elastic strand to be disposed in front of some needles and behind other needles in selected order, the elastic strand being laid behind several needles and in front of a lesser number of needles to produce outwardly bulged portions in the fabric to thereby form a pattern, means for advancing the sinkers at the knitting point so as to knit all wales of the body yarn on top of the nibs of the sinkers to thus produce a very loose stitch so that the contraction of the fabric by the elastic yarn will cause the plurality of wales having the body yarn laid behind the same to bulge outwardly to produce a pattern effect, the body yarn being heavier than it is possible to knit the same without the sinkers being advanced at the knitting point, a member pivoted adjacent the needle circle and projecting over the needle circle and then projecting downwardly inside of the needle circle, a roller rotatably mounted on the lower end of said member and disposed at an angle to the line of travel of the needles for resting on the fabric and holding it against the inner ends of the sinkers to cause the fabric to shed from the needles upon lowering of the needles, and pattern controlled means for raising and lowering said roller to move it to operative or inoperative position, as desired.

3. In a circular knitting machine having needles and sinkers and means for feeding body yarn to the needles and means for feeding an elastic strand to the needles, pattern controlled means for selectively raising some of the needles so as to cause the elastic strand to be disposed in front of some needles and behind other needles in selected order, the elastic strand being laid behind several needles and in front of a lesser number of needles to produce outwardly bulged portions in the fabric to thereby form a pattern, means for advancing the sinkers at the knitting point so as to knit all wales of the body yarn on top of the nibs of the sinkers to thus produce a very loose stitch so that the contraction of the fabric by the elastic yarn will cause the plurality of wales having the body yarn laid behind the same to bulge outwardly to produce a pattern effect, a member pivoted outside the needle circle and projecting over the needle circle and downwardly inside the needle circle and having a member on its lower end for resting on the fabric to hold the fabric down against the inner ends of the sinkers, and pattern controlled means for raising and lowering the member on its pivot out of and into engagement with the fabric.

4. In a circular knitting machine having needles and sinkers and means for feeding body yarn to the needles and means for feeding an elastic strand to the needles, pattern controlled means for selectively raising some of the needles so as to cause the elastic strand to be disposed in front of some needles and behind other needles in selected order, the elastic strand being laid behind several needles and in front of a lesser number of needles to produce outwardly bulged portions in the fabric to thereby form a pattern, means for advancing the sinkers at the knitting point

point so as to knit all wales of the body yarn on top of the nibs of the sinkers to thus produce a very loose stitch so that the contraction of the fabric by the elastic yarn will cause the plurality of wales having the body yarn laid behind the same to bulge outwardly to produce a pattern effect, the body yarn being heavier than it is possible to knit the same without the sinkers being advanced at the knitting point, a member pivoted outside the needle circle and projecting over the needle circle and downwardly inside the needle circle and having a member on its lower end for resting on the fabric to hold the fabric down against the inner ends of the sinkers, and pattern controlled means for raising and lowering the member on its pivot out of and into engagement with the fabric.
